PISTON ENGINE-POWERED DRILL MOTOR

Buford J. Schramm, 14805 S. Interstate 10, Tempe, Ariz.
85281, and Robert G. Everts, 2118 E. Birchwood Ave.,
Mesa, Ariz. 85204

Filed Oct. 23, 1974, Ser. No. 517,292

Term of patent 14 years

Int. Cl. D8—01

U.S. Cl. D8—69

FIG. 1

Fig. 2

FIG. 3

FIG. 4

FIG. 5

FIG. 1 is a right rear oblique view of a drill motor according to the invention;

FIG. 2 is a side elevation looking toward the collet of the drill motor, from the right in FIG. 1;

FIG. 3 is a top view of the drill motor;

FIG. 4 is a side elevation of the drill motor, showing the rear side which is concealed in FIG. 1; and

FIG. 5 is a side elevation looking toward the opposite end of the drill motor from the view of FIG. 2.

We claim:

The ornamental design for a piston engine-powered drill motor, as shown.
